FLOWER POT

Alvis D. Wilkinson, Box 25118,
Oklahoma City, Okla. 73125

Filed May 4, 1972, Ser. No. 250,467

Term of patent 14 years

Int. Cl. D11—02

U.S. Cl. D35—3 A

FIG. 1

FIG. 2

FIG. 3

FIG. 4

FIG. 5

FIG. 6

FIG. 1 is a side elevation of a flower pot showing my new design;

FIG. 2 is a side elevation as viewed rotated 90° from FIG. 1;

FIG. 3 is a top plan view thereof;

FIG. 4 is a bottom plan view thereof;

FIG. 5 is a side elevation of a second modified embodiment of the flower pot illustrated in FIG. 1;

FIG. 6 is a side elevation rotated 90° from FIG. 5;

FIG. 7 is a side elevation of a third modified embodiment of the flower pot illustrated in FIG. 1;

FIG. 8 is a side elevation rotated 90° from FIG. 7;

FIG. 9 is a side elevation of a fourth modified embodiment of the flower pot illustrated in FIG. 1;

FIG. 10 is a side elevation rotated 90° from FIG. 9;

FIG. 11 is a top plan view thereof; and

FIG. 12 is a bottom plan view thereof.

I claim:

The ornamental design for a flower pot, substantially as shown and described.
